FIG. 3.

FIG. 2.

UNITED STATES PATENT OFFICE

FITZHUGH EARLY SCOTT AND LAWRENCE R. BRYANT, OF RICHMOND, VIRGINIA, AS
SIGNORS TO LIGGETT & MYERS TOBACCO COMPANY, OF NEW YORK, N. Y., A COR-
PORATION OF NEW JERSEY

METHOD OF AND MACHINE FOR PACKAGING CIGARETTES

Application filed July 24, 1931. Serial No. 552,992.

Our present invention relates to a method of and machine for packaging cigarettes and has to do more particularly with a method of and means for packaging cigarettes with a 5 humidifying insert included in the finished package.

At the present time the more popular brands of cigarettes now upon the market are enclosed in what are known as "cup" 10 or "pouch" packages consisting of an inner wrapper of foil or foil and paper and an outer wrapper of relatively stiff paper. Cigarette packages of this type are made by automatic machinery, which operates to successively select or segregate a given number 15 of cigarettes, as, for instance, 20 cigarettes from a hopper or magazine and then enclose the same within the cup or pouch, the latter being usually formed about hollow mandrills carried by a rotary turret in the 20 pockets or carriers of which the groups of cigarettes have been previously inserted. The cigarettes are then pushed out of the 25 pockets along with the "cup" or "pouch" and the projecting ends of the inner foil or foil and paper wrapper folded to closed position and sometimes sealed, as by an overlying revenue stamp, or otherwise.

We have shown our improvements as applied to such a known type of machine, although we do not wish to be understood as limiting ourselves to the particular machine illustrated and described except as we may be limited by the appended claims. Briefly and generally stated, our invention includes the method of packaging cigarettes with a humidifying insert therein, which consists in segregating a group of cigarettes from a mass, then associating a humidifying insert with said group, and then delivering the said group of cigarettes along with the insert into a prepared wrapper, such as a formed "pouch" and sealing the same; and further includes a means for automatically feeding the humidifying inserts to successively selected groups of cigarettes prior to the step of inserting the group, with its associated insert, into a wrapper such as a "pouch" or "cup".

In order to enable others skilled in the art

to understand, make and use our said invention, we will now proceed to describe a preferred embodiment thereof, which is illustrated in the accompanying drawings, wherein.—

Fig. 1 is a side elevation of a portion of an automatic machine for packaging cigarettes, with our improvements incorporated therein, and including the means for automatically feeding the inserts;

Fig. 2 is a similar view looking at the opposite side of the cigarette carrying turret shown in Fig. 1;

Fig. 3 is a sectional view taken on the broken line 3—3 of Fig. 2;

Fig. 4 is a view of one form of "humidifying insert," and

Fig. 5 is a perspective view of a cigarette package made according to our invention, a portion of the walls thereof being broken away to expose the "insert."

In the said drawings the reference numeral 1 designates an intermittently rotatable shaft upon which is mounted a turret frame 2, carrying at its periphery a plurality of spaced cigarette pockets 2^a. As all the pockets are of like construction a description of one will suffice. Each pocket consisting of a fixed upstanding side wall 3, having an overhanging top flange 4, and a movable upstanding side wall 5, having a bottom section 6, extending toward and meeting the inner face of the opposite fixed side wall 3, so that said side walls 3 and 5 and bottom and top walls 4 and 6 constitute a pocket 2^a, of a size and shape to hold a group or selected number of cigarettes, as, for instance 20, to be included in each package. The overhanging top flange 4 of the fixed wall 3, terminates short of the inner face of the movable side wall 5, for a purpose presently to be described.

Each movable side wall 5, is mounted upon a slideable bar 7, each bar carrying a roller 8, mounted for rolling movement in a cam-slot 9, formed in the face of a fixed cam-plate 10, which is mounted concentric with the intermittently rotating shaft 1.

The cam-slot 9, as more clearly shown in Fig. 1, is so arranged that the movable side

100

wall 5, with its bottom 6, may be progressively moved relative to the fixed wall 3, and its overhanging top flange 4, so that as the turret rotates in the direction of the arrow shown in Fig. 1, the group of cigarettes in each pocket will be slightly compressed. The letter A, in Fig. 1, indicates approximately the station at which the groups of cigarettes are pushed endwise into the pockets 2^a as they successively appear at said station so that when they reach the discharge position B, the groups of cigarettes will be pushed successively from the pockets 2^a, into the pockets 12, formed by the mandrels 13, carried by a second intermittently rotating turret 14, moving in the direction of the arrow indicated in Fig. 1. As the cigarette pockets 2^a carried by the turret 2, register with the pockets 12, carried by the turret 14, a plunger indicated by the numeral 15, transfers the cigarettes from one pocket to the other, a suitable "cup" or "pouch" having already been formed about each hollow mandrel 13, before it reaches the position B, as is well understood in machines of this type.

According to our invention we propose to associate with each group of cigarettes in each of the pockets 2^a, a humidifying element or insert, which in the present instance, is in the form of a cylinder or tube carrying moisture. As shown in Fig. 4, this humidifier may consist of an open-ended tube 16 formed of wax paper or the like, and which carries a filler of moistened absorbent material 16^a, all as shown and described in the co-pending application for patent, Dr. Paul M. Groce and George H. Flowers, filed July 15th, 1931, serially numbered 550,978.

In order to feed the humidifying inserts 16 or tubes 16, into the pockets carried by turret 2, and in association with the cigarettes therein, we provide each pocket with a movable substantially hook-shaped top wall 17, having the upper face of its end 18, slightly beveled and projecting downwardly into the pocket 2^a and positioned to enter the space between the overhanging wall 4, of the fixed side wall 3, and the inner face of the movable side wall 5, as clearly shown in Fig. 1. Each top wall 17 is formed as a part of a casting pivoted at 19 to the outer face of the fixed side wall 3, and each has a downwardly and rearwardly trailing arm 20, carrying at its end a roller 21, which normally rides on a track 22, also formed on the fixed turret plate 10. A spring 23 (Fig. 3) is coiled about the pivot pin 19, of each pocket, the free projecting ends of the spring acting respectively upon the fixed wall 3, and the casting of the overhanging top wall 17, so as to normally hold the top wall 17, in position to have its downwardly projecting end 18 enter the pocket between the overhanging portion 4 of the fixed wall 3, to completely close the cigarette pockets, and to engage and push the

humidifying inserts into position in association with the group of cigarettes in the pocket.

The track 22, is provided at one point with a cam-plate 24, as more clearly shown in Fig. 1, and with which the roller 21 carried by the arm 20, contacts during the rotation of the turret so as to move the top wall 17 on its pivot at the moment the pockets successively arrive at the station C, indicated in Fig. 1, and thus raise the downwardly projecting portion 18, from the pocket and leave a free space for the insert to enter the top of the pocket and become associated with the cigarettes therein.

The humidifying inserts 16, are carried by a hopper or magazine 25, in the forward open end of which is mounted a rotatable drum 26, carried by a shaft 27, driven by a belt 28, from the intermittently rotating main shaft 1, or from any other suitable source, said shaft 27, and its drum 26, being so timed that an insert will be delivered into each cigarette pocket 2^a as the pockets successively appear at the station C. The drum 26, carries longitudinally extending peripheral depressions 26^a, into which the humidifying inserts may enter as the drum rotates in the direction of the arrow shown in Fig. 1. The inserts are prevented from falling from the pockets by a curved plate 29, having a depending portion 30, so positioned that the inserts will be discharged from the depressions at the proper moment to permit them to fall into the cigarette pockets. A rotatable wheel or brush 31, is mounted in the hopper 25, above the drum 26, and operates to assist the inserts in finding their way into the depressions in the periphery of the drum.

The operation of the mechanism described is as follows:

Assuming the turrets 2 and 14 to be rotating intermittently in the direction of the arrows, when the cigarette pockets of turret 2, reach the station A, at which the pockets have their largest dimensions, a group of cigarettes is fed into each pocket. As the turret continues to rotate in the direction of the arrow, the movable wall 5, is moved relative to the fixed wall 3, of each pocket, so that the cigarettes will become gradually compressed, and as the pockets successively appear at the station C, the compression is relieved by the rollers 8, moving in the flattened portion 32 of the cam groove 9, and at this moment the overhanging top wall 17 will be moved back or to open position as the roller 21 engages the cam 24 of the cam track 22. At this point a humidifying insert which has been brought to position by the drum 26, drops into the open pocket, whereupon the overhanging top wall 4 is immediately brought to position to cause its downwardly extending portion 18 to enter the cigarette pocket directly above the insert.

The group of cigarettes together with the inserts are thereafter again placed under compression by the upward movement of the movable wall 5, and are held under compression until the pocket is brought opposite and in register with a pocket 12, in the mandril turret 14. As heretofore stated each mandril carries a formed "cup" or "pouch" like that shown in the cigarette package illustrated in Fig. 4, with its open end arranged opposite an open side of the cigarettes, whereupon the plunger 15, is brought into action and the group of cigarettes along with its insert are pushed endwise into the "cup" or "pouch" and at a later position of the turret 14, the projecting end of the pouch is folded to closed position and thereafter pushed out of its hollow mandril in a finished state, to be then stamped or otherwise sealed, as desired,—these several operations occurring successively and in regular sequence during the intermittent motion of the turrets.

We have not illustrated herein the mechanism for pushing the separate groups of cigarettes into the cigarette pockets, nor have we illustrated the mechanism for forming the "cups" or "pouches" and for closing them, as these mechanisms are all well known in the art and do not constitute a part of our present invention, the latter residing primarily in the application to such a known cigarette packaging machine of a means for so compressing the groups of cigarettes to be packed and associating with each group a humidifying insert, such as herein described, so that each group of cigarettes wrapped or packaged by the machine will have incorporated in the sealed or closed package, a humidifying insert which will raise the moisture content of the tobacco in the packaged cigarettes,—all as more clearly described in the before mentioned application for patent of Groce and Flowers.

While we have illustrated and described a preferred embodiment of our invention, and have shown the same in connection with a known type of cigarette packaging machine, we do not wish to be understood as limiting ourselves to the precise mechanism shown or to its employment in connection with the packaging machine shown, except as we may be limited by the appended claims. Obviously minor changes may be made without departing from the spirit of the invention, and it will be further obvious that the mechanism shown may be employed in connection with the packaging of other articles besides cigarettes and wherein it is desired to associate an insert of some kind with the packaged articles.

What we claim is:

1. The method of packaging cigarettes with a humidifier insert, which consists in segregating a group of unwrapped cigarettes,

compressing the group, associating a humidifying insert with said group and in direct contact with certain of the cigarettes therein, and then delivering the said group of cigarettes along with the insert into a prepared wrapper and closing the same, whereby the moisture from the humidifying element will be free to be taken up by the tobacco in the wrapped package.

2. The method of packaging cigarettes with a humidifying insert in the package to increase the moisture content of the tobacco in the packaged cigarettes, which consists in segregating a group of unwrapped cigarettes, associating a humidifying insert with said group and in direct contact with the cigarettes, and then pushing the said group with its insert endwise into a pre-formed cup or pouch package and closing the same.

3. The method of packaging cigarettes with a humidifying insert in each package to increase the moisture content of the tobacco in the package, which consists in successively advancing groups of unwrapped cigarettes to be packaged, associating a humidifying insert with each group during such advance and before the group is wrapped, advancing a succession of formed pouch-like containers and bringing them into register with the advancing cigarette groups, and then assembling the said containers and groups to form filled and closed packages of cigarettes each containing a humidifying insert, whereby the moisture from the humidifier will be free to be taken up by the tobacco in the packages.

4. The method of packaging cigarettes with a humidifying insert in each package to increase the moisture content of the tobacco therein, which consists in intermittently advancing in a circular path successive groups of unwrapped cigarettes to be packaged, associating a humidifying insert with each group before the groups are wrapped at a predetermined point in said advancing path, simultaneously advancing successively pre-formed pouch-like containers and bringing them into register with the advancing cigarette groups, and then assembling the said containers and groups of cigarettes to form closed packages each containing cigarettes and an associated humidifying insert.

5. In a machine for packaging cigarettes, a turret carrying a plurality of cigarette pockets, each having an opening in a wall thereof, a closure for said opening, means for opening and closing the closure, and means for feeding a humidifying insert into direct contact with the cigarettes in each pocket when the said closure is in open position.

6. In a machine for packaging and for increasing the moisture content of the tobacco in packaged cigarettes, an intermittently rotating turret carrying a plurality of pockets,

each to receive a group of unwrapped cigarettes, each pocket having an opening leading thereto and a movable closure therefor, means for compressing the cigarettes while in said pockets, and means for feeding a humidifying insert through the said opening and into direct contact with the cigarettes in each pocket.

7. In a machine for packaging cigarettes, 16 an intermittently rotating turret carrying a plurality of pockets, each formed of two relatively movable walls, a movable closure pivoted to one of said walls and having a portion adapted to enter its associated pocket, 15 means for moving the closure on its pivot to open and closed position, and means for feeding a humidifying insert into each pocket when its closure is in open position.

8. In a machine for packaging cigarettes, 20 an intermittently rotatable turret having a plurality of spaced pockets, each consisting of two relatively movable walls with an opening leading into each pocket, a pivoted closure for said opening, means operated during rotation 25 of the turret to move the closure to open position at a predetermined point, and means operating to feed an insert into each pocket when its associated closure is in open position.

9. In a machine for packaging cigarettes with humidifying inserts therein to increase the moisture content of the tobacco in the packages, an intermittently rotating turret carrying a plurality of pockets, each having 30 relatively movable walls constructed to provide an opening leading into the top of each pocket when in an upward position, an independent closure member having a portion movable into and out of said opening, means 35 for feeding a humidifying insert through said opening and into each pocket when the said closure is in open position, and means for thereafter moving the closure to closed position.

10. In a machine for packaging cigarettes with a humidifying insert in each pocket, a rotatable turret carrying a plurality of cigarette pockets, each pocket having an opening in a wall thereof, a movable closure for said opening, means for compressing the cigarettes in the pockets, and for relieving the compression, means for opening the closure, means for feeding an insert into the pockets when their associated closures are in open position, and means for thereafter again placing the cigarettes in the pockets under compression.

11. In a machine for packaging groups of cigarettes, with a humidifying insert associated with each group, an intermittently rotating turret carrying a plurality of spaced cigarette pockets, each having an opening therein, a movable closure for said opening, means for moving the closure to open and closed position, a magazine for humidifying

inserts, and means for feeding the inserts from the magazine into each pocket when its movable closure is in open position.

12. In a cigarette packaging machine, a pair of intermittently rotating turrets, one carrying a plurality of cigarette pockets each with an opening in a wall thereof, and the other a plurality of pouch carrying mandrels, means for feeding a humidifying insert in association with the cigarettes in each pocket 75 and through the opening leading thereto, means for thereafter compressing the cigarettes and means for forcing the cigarettes endwise from each pocket into a pouch mandrel of the other turret. 80

13. In a machine for packaging cigarettes with a humidifying insert in each package, an intermittently rotatable turret having at its periphery a plurality of cigarette carrying pockets, each having an opening therein, 85 a closure pivoted to a wall of each pocket, each closure having a tail piece, a fixed cam arranged for engagement by said tail piece to move the closure to open position at a predetermined point, and means for feeding a 90 humidifying insert into each pocket when the closure is in open position.

14. In a machine for packaging cigarettes with a humidifying insert in each package, a rotatable turret having a plurality of cigarette-carrying pockets at its periphery with an opening leading into each pocket, a hook-shaped closure pivoted to a wall of each pocket, means for normally holding the closure in closed position, a cam for moving the 100 closure to open position at a predetermined point in the travel path of the turret, and means for feeding a humidifying insert into each pocket when the closure is in open position. 105

15. In a machine for packaging cigarettes with a humidifying insert in each package, an intermittently rotating turret carrying a plurality of radially arranged pockets, each with an opening in an end wall thereof, a pivoted 110 closure associated with each pocket, means for normally holding the closure in closed position, means for opening the closure at a predetermined point in the travel path of the turret, means for compressing cigarettes in each pocket during a portion of the travel path of the turret, means for relieving the compression at the point where the inserts are fed into each pocket, and means for thereafter again placing the cigarettes under compression. 115

16. In a machine for packaging cigarettes with humidifying inserts in each package, a plurality of pockets each adapted to carry a group of cigarettes, each pocket having an opening through a wall thereof, a closure for said wall, means for opening and closing the closure, means for moving the cigarette pockets through an endless path, and means for depositing a humidifying insert into 130

each pocket when the closure is in its open position.

17. In a machine for packaging cigarettes with a humidifying insert in each package, an intermittently rotating turret, a plurality of pockets carried by said turret, each pocket having an opening in a wall thereof, a closure associated with each pocket for opening and closing said opening, means for moving the closure to open position, a magazine for the inserts, means for delivering the inserts from the magazine into the cigarette pockets when the closure member is in open position, and means for thereafter moving the closure to closed position.

Signed at Richmond, in the county of Henrico and State of Virginia this 20th day of July, A. D. 1931.
